COMBINED CIGARETTE PACKAGE CASE AND LIGHTER

Arthur A. Noymer, Marblehead, Mass., assignor to Noymer Manufacturing Company, Boston, Mass.

Filed Jan. 17, 1961, Ser. No. 63,591

Term of patent 14 years

(Cl. D87—3)

Fig. 1.

Fig. 2.

Fig. 3.

Fig. 4.

FIG. 1 is a top plan view of a combined cigarette package case and lighter showing my new design;

FIG. 2 is a front elevational view thereof;

FIG. 3 is a side elevational view thereof; and

FIG. 4 is a bottom plan view thereof.

I claim:

The ornamental design of a combined cigarette package case and lighter, substantially as shown.
